Filed Apr. 28, 1972, Ser. No. 248,796

Term of patent 7 years

Int. Cl. D19—03

U.S. CL D74—5 R

FIG. 1

FIG. 1 is a perspective view of a perpetual calendar having display area showing my new design; and FIG. 2 is a side elevational view thereof.

The device includes an upper area portion suitable for display purposes, as indicated by the irregular line therein, and a lower calendar portion containing five rows of movable blocks bearing enumeration coinciding with the days of the month and a sixth row of blocks bearing enumeration and letters indicating the month and year.

I claim:

The ornamental design for a perpetual calendar having display area, as shown.
